UNITED STATES PATENT OFFICE.

LOUIS W. RICE, OF NEW YORK, N. Y., ASSIGNOR TO BERNARD RICE'S SONS, INC., OF NEW YORK, N. Y., A CORPORATION OF NEW YORK.

DESIGN FOR A BOX OR SIMILAR ARTICLE.

Application filed May 18, 1928. Serial No. 26,753. Term of patent 7 years.

To all whom it may concern:

Be it known that I, LOUIS W. RICE, a citizen of the United States, residing at 325 Fifth Avenue, New York city, in the county of New York, and State of New York, have invented a new, original, and ornamental Design for a Box or Similar Article, of which the following is a specification, reference being had to the accompanying drawing, forming part thereof.

Fig. 1 is a top plan view of the box or similar article, and

Fig. 2 is a side view with the body of the box shown in broken lines. The top or cover of the box is the dominant feature of my design.

I claim:

The ornamental design for a box or similar article, substantially as shown and described.

LOUIS W. RICE.
